CAP

Irving E. Soboroff, Chicago, Ill., assignor to
Soboroff-Rosenwald Company, Chicago, Ill., a
corporation of Illinois

Application February 10, 1941, Serial No. 378,173

3 Claims. (Cl. 2—196)

This invention relates to a cap, and more particularly to a cap having ear flaps connected together by extensions at the rear of the cap.

In the past, it has been the practice in the case of caps used by farmers, hunters, and others to provide ear flaps which could be turned upwardly when not in use, and which are connected at the rear of the cap by extensions adapted to cover the neck of the wearer when the flaps are turned downwardly. Such caps are frequently made of corduroy material and include ribbons for tying the flaps together over the top of the cap when the flaps are folded upwardly.

I have found that in the use of these caps considerable difficulty is encountered in turning the flaps downwardly due to the fact that they are connected by circular extensions at the rear of the cap. As a matter of fact, the wearer of such a cap usually has to remove the cap from his head in order to turn the flaps and their rear integral or connected extension downwardly and then to put the cap back on his head. The reason for this difficulty is due to the fact that the extensions are integral and are formed so as to hug closely the crown portion of the cap when folded upwardly and likewise to closely hug the neck of the wearer when the flaps are folded downwardly.

It is an object of the present invention to provide a cap which eliminates the above discussed disadvantages of previous caps.

Another object of this invention is to provide a cap having ear flaps connected with extensions and wherein the flaps and the extensions may be folded downwardly or upwardly with reference to the cap without necessitating removal of the cap from the head of the wearer.

In accordance with the general features of this invention, there is provided a cap including a crown portion and depending ear flaps adapted to be folded upwardly over the sides of the crown portion; these ear flaps having aligned extensions at the rear of the cap and being provided with juxtaposed separable portions detachably connected together by fastening means.

In accordance with the preferred embodiment of the invention, the fastening means is a slideable type fastener or a so-called "zipper" and is arranged so as to be manually operable to attach the flap extensions when the flaps are folded upwardly and facilitate turning of the flaps downwardly without necessitating removal of the cap from the head of the wearer. Also, the fastener is so arranged so as to be manually operable when the flaps or extensions are turned

downwardly whereby the extensions may be connected or disconnected over the neck of the wearer.

Other objects and features of this invention will more fully appear from the following detailed description taken in connection with the accompanying drawing, which illustrates a single embodiment thereof, and in which:

Figure 1 is a rear perspective view of the cap showing it applied to the head of a wearer;

Figure 2 is a fragmentary view of the rear of the cap showing the strings connecting the ear flaps disconnected and also showing the fastener between the extensions on the flaps in a disconnected position; and

Figure 3 is a rear view of the cap with the ear flaps and their extensions turned downwardly and connected together by the sliding type fastener.

As shown on the drawing:

The reference character 10 designates generally the crown portion of a so-called "hunter's or farmer's type" of cap which may be made of any suitable material such, for example, as corduroy. The front of the cap is provided with the usual visor 11. Integrally connected with the side portions of the crown 10 of the cap are ear flaps 12—12 which, when folded upwardly may be connected together by tie strings or ribbons 13—13, as shown in Figure 1.

The ear flaps or muffs 12 may be made of any suitable construction and are of such a shape and size as to cover the ears of the wearer when they are folded downwardly. Each of the ear flaps 12 is provided with a rearward extension 14; these rear extensions being aligned at the rear of the crown portion 10 of the cap and in accordance with the features of this invention are connectable and disconnectable from each other.

The extensions 14—14 have juxtaposed portions which are interconnected by a sliding type fastener designated generally by the reference character 15, and which in the trade is known as a "zipper type" of fastener. This zipper type of fastener, as is known, includes the usual handle or finger piece 16 for manipulating the same.

It will be perceived that the sliding type fastener 15 is disposed in a vertical position between the juxtaposed rear extremities of the ear flap extensions 14—14. Also, the finger piece or handle 16 is disposed in a position where it is readily accessible for manipulating the fastener to connect or disconnect the two extensions

14—14 over the rear side of the medial portion of the crown 10 of the cap.

In Figure 1, I have illustrated the ear flaps and their extensions folded upwardly alongside of the crown portion 10 of the cap with the extensions 14—14 connected together by the fastener 15. When it is desired to lower the flaps 12—12, the ribbons or strings 13 are first unfastened so as to detach the flaps from each other. Thereafter, without the necessity of removing the cap from the wearer, the ear flaps and their extensions 14—14 may be turned downwardly by first manipulating the sliding fastener, as shown in Figure 2, to disconnect the two extensions. By disposing this fastener at the medial plane of the cap, it is possible to separate the circular extensions 14—14 substantially midway between the flaps 12—12. This breaks the continuity of the circular flaps formed by the two extensions 14—14 on the rear of the ear pieces 12 and enables them to be folded downwardly along with the flap without requiring removal of the cap from the head of the wearer.

After the flaps and extensions are turned downwardly, as shown in Figure 3, the sliding type fastener 15 may again be manipulated by pulling the finger piece 16 downwardly. This results in the closing of the gap between the extensions or rear flaps 14—14 and thereby connects them together over the neck of the wearer.

To raise the ear flaps 12 and their extensions 14 the operations as described above are followed in reverse order as is obvious.

I claim as my invention:

1. As an article of manufacture, a cap including a crown portion and ear flaps adapted to be folded upwardly over the sides of the crown portion, said ear flaps having aligned extensions at the rear of the cap, and a sliding type vertically disposed fastener connecting said extensions and manually operable to separate said extensions when said flaps are folded upwardly to facilitate turning of the flaps downwardly and thereafter manually operable to connect the extensions together over the rear of the neck of the wearer.

2. As an article of manufacture, a cap including a crown portion and ear flaps adapted to be folded upwardly over the sides of the crown portion, said ear flaps having cooperable extensions at the rear of the cap and said extensions having juxtaposed vertical portions, and detachable fastening means connecting said portions together and manually operable to separate said portions and extensions when said flaps are folded upwardly to facilitate turning of the flaps downwardly and thereafter manually operable to connect said portions together over the rear of the neck of the wearer all without requiring removal of the cap from the head of the wearer.

3. In a cap including ear flaps foldable upwardly and downwardly at the option of the wearer, rear extensions on said flaps and a vertically slidable fastener for connecting and disconnecting said extensions at the rear of said cap without requiring removal of the cap from the person's head.

IRVING E. SOBOROFF.
